ATTORNEY

UNITED STATES PATENT OFFICE.

JOHN ALDEN HIGGS, OF ROXBURY, MASSACHUSETTS

COLLAR-BUTTON.

1,278,927.

Specification of Letters' Patent. Patented Sept. 17, 1918.

Application filed March 27, 1918. Serial No. 225,013.

To all whom it may concern:

Be it known that I, JOHN ALDEN HIGGS, a citizen of the United States, residing at Roxbury, in the county of Suffolk and State of Massachusetts, have invented certain new and useful Improvements in Collar-Buttons, of which the following is a specification.

This invention relates to an improved collar button and the principal object of the invention is to provide a collar button which can be formed of sheet metal and which will be so constructed that it will not slip loose from the collar band or collar.

Another object of the invention is to so construct this collar button that it may conform to the contour of the neck thus permitting the button to be held securely in place without inconvenience to the wearer.

Another object of the invention is to so construct this button that it will not bind the tie and to further so construct the button that it may be easily put in place.

Another object of the invention is to provide a sheet metal collar button which will be of simple construction and easy to form.

This invention is illustrated in the accompanying drawings, wherein:

Figure 1 is a view showing the improved collar button in front elevation,

Fig. 2 is a view showing the collar button in side elevation,

Fig. 3 is a plan view of the blank from which the button is formed,

Fig. 4 is a longitudinal sectional view taken along the line 4-4 of Fig. 3,

Fig. 5 is a view in section showing the tongue of the blank bent to extend from the blank;

Fig. 6 is a view similar to Fig. 5 showing the tongue provided with a second bend to extend upwardly, and

Fig. 7 is a view similar to Fig. 6 showing the tongue bent downwardly.

This improved collar button will be formed from a sheet metal blank shown in Fig. 3 and indicated in general by the numeral 10, the blank being struck from sheet metal and being preferably formed of pliable sheet metal so that when in use, this button may conform to the contour of the neck.

This blank is provided with a wide base portion 11 from which extends the tongue 12 positioned between the side wings 13 and

flaring toward its outer end as shown in Figs. 1 and 3. This tongue 12 is bent at 55 right angles to extend outwardly from the base 11 and is then bent upwardly and doubled back upon itself to extend downwardly as shown in Figs. 6 and 7 after which the inner and outer folds will be pinched together as shown in Fig. 2 and provide a head 14 at the outer end of a neck 15. The head extends above and below the neck and tapers toward its upper end as shown in Fig. 1 so that when in place, and passed through a collar button-hole, the collar cannot easily slip off of the button.

When this button is in use, it will be put in place with the head and neck extending through the button-hole of the neck-band 70 of a shirt and the collar will then be connected with the button by passing the head of the button through the button hole thus placing the collar upon the neck 15. The base 11 will bend when the collar band is 75 fastened and will thus conform to the contour of the neck preventing the collar button digging into the neck. As the neck 15 and the inner end portion of the tongue 12 will extend through the button-hole, there will 80 be created a binding action between the collar band and the side extensions 13 of the collar button thus tending to prevent slipping of the button. The collar will not be liable to slip from the button, as the head 85 extends above and below the button hole and thus tends to securely hold the collar in place. This collar button will further have no binding upon the neck-tie due to the fact that it is flat and therefore the neck-tie may 90 slip easy and will not be caused to bind in the collar.

What is claimed:

1. A collar button formed from a blank of pliable material having a base and a side tongue extending from the base, the base upon opposite sides of the tongue being cut to provide side extensions, and the tongue increasing in width toward its outer end, said tongue being bent adjacent its inner end to extend outwardly at substantially right angles to the base to provide an outwardly extending neck and being then bent to extend upwardly and doubled back upon itself to provide a head at the outer end of 105 the neck extending above and below the neck.

2. A collar button having a base provided with a side tongue extending from one side of the base at a point intermediate its length, the tongue increasing in width toward its outer end and being bent adjacent its inner end to extend outwardly and provide a neck, the tongue being then bent upwardly and bent back upon itself to provide a head at the outer end of the neck extend-
- 5

ing above and below the neck and increasing in width toward its lower end.

In testimony whereof I affix my signature in presence of two witnesses,

JOHN ALDEN HIGGS.
